L. WOLLBRINCK

SPARK PLUG

Filed Apr. 24, 1922

Inventor:
Louis Wollbrinck

By John C. Higdon
Attorney

UNITED STATES PATENT OFFICE.

LOUIS WOLLBRINCK, OF ST. LOUIS, MISSOURI.

SPARK PLUG.

Application filed April 24, 1922. Serial No. 556,166.

To all whom it may concern:

Be it known that I, LOUIS WOLLBRINCK, a citizen of the United States, residing at St. Louis, in the State of Missouri, have invented certain new and useful Improvements in Spark Plugs, of which the following is a specification containing a full, clear, and exact description, reference being had to the accompanying drawing, forming a part hereof.

My invention consists in the novel construction and arrangement of parts herein-after particularly described and distinctly claimed.

15 The object of my invention is to provide a spark-plug with an improved elongated form of amperage-booster, which will give a spark several times stronger than that produced by an ordinary spark-plug, and 20 which amperage-booster shall be enclosed within and protected by a detachable part of the plug, that can be quickly removed from the casing or base of the plug, for cleaning or repairs, without removing said 25 casing from the motor-cylinder.

A further object of my invention is to provide an improved spark-plug which shall be practically foul-proof, and capable of producing a spark of great strength in 30 engines having the very highest compression.

A further object is to provide an improved spark-plug in which the main porcelain (which carries the central electrode) 35 can be quickly removed and cleaned, or a new porcelain substituted, while the casing or base of the plug remains in the cylinder.

A further object is to provide an improved spark-plug with a separate binding-post porcelain, having a cylindrical metallic casing secured thereto by crimping the metal around the same, to take care of expansion and contraction, without cracking or breaking said porcelain.

45 A further object of my invention is to provide an improved spark-plug central electrode, that is carried by, and detachable with, the main porcelain, and which electrode is provided with an abutment or upset shoulder which makes an oil-tight joint with the inner end of said porcelain, and prevents oil from being forced upwardly through the bore of the latter, to the amperage-booster.

And finally, the general object of my invention is to provide an improved spark-plug having the construction and advantages above enumerated, which shall yet be simple and of low cost.

In the drawings, 55
Fig. 1 is a side-elevation of my invention.
Fig. 2 is a vertical longitudinal section of the same, taken on the line 2—2 of Fig. 1.

Fig. 3 is an enlarged fragmentary detail view of the parts composing the amperage- 65 booster.

Fig. 4 is an enlarged fragmentary detail view of the binding-post porcelain and its metallic casing, illustrating the manner in which the latter is crimped around the porcelain, and 70

Fig. 5 is an enlarged detail view of the inner end of the main porcelain member, and a portion of the central electrode carried thereby.

75 The numeral 1 designates the casing or base of the plug, which is made of suitable metal, with a threaded portion 2, for the well-known purpose of permitting the said casing to be screwed into the combustion-chamber of the engine or motor, by applying a wrench or pliers to the usual hexagonal portion 3.

A fixed electrode 4 projects from the said casing or base 1, upon the interior thereof, 85 and extends radially therein to a point near the axis of said casing, so as to cooperate with the adjacent central detachable electrode 5; both of said electrodes being set to avoid any projection thereof beyond the 90 inner end of said casing, to avoid accidental bending or breakage, which might occur if either of said electrodes projected free beyond the casing. By my construction, as just described, the spark points are thoroughly protected in the plug, and cannot 95 be accidentally bent or broken by contact with external objects.

The numeral 6 designates the main porcelain or insulation, which is provided with a 100 central longitudinal passage 7 through which extends the central metallic electrode 5.

Said central electrode 5 is provided or formed with an abutment or upset shoulder 105 9, which is located within a recess 10 at the inner end of said main porcelain 6, and is clamped upon suitable packing 11, to make

an oil-tight joint between said electrode and the lower end of the said porcelain, and thereby prevent the passage of oil or gas upwardly through the central bore of the porcelain.

5 The lower end of the said central electrode 5 extends to a position closely adjacent to the free inner end of the said fixed electrode 4, so that sparks may be formed 10 between said electrodes when a current of electricity is passed through them.

The upper portion of the said central electrode 5 has a nut 12 threaded upon it, and the latter clamps a gasket or packing 15 device 14 firmly into contact with the upper end of the said main porcelain 6, and at the same time forces the said abutment or shoulder 9 securely into contact with the said packing 11 at the opposite end of the 20 bore in said porcelain.

Said main porcelain 6 has an annular shoulder 15 upon its exterior, at about the center of its length, and said shoulder makes a tight joint with the seat 16 upon the 25 interior of the said casing 1 when forced into contact with a gasket or packing 17 that is disposed between said seat and said shoulder.

A metallic thimble or sleeve 18 has its lower or inner portion provided with 30 external screw-threads 19, which engage internal screw-threads 20 formed upon the interior of the upper or outer end of said base 1 of the plug, so that said thimble is thereby detachably threaded in the upper 35 end of said base.

Said thimble 18 has the usual hexagonal exterior 21, to be engaged by a wrench or pliers, in detaching or attaching it.

40 The lower (or inner) end of the said thimble 18 engages the said annular shoulder 15 of said main porcelain, or insulating member 6, and forces said shoulder into contact with the said gasket 17, to make a tight joint, as previously stated. Fig. 2.

45 A separate binding-post porcelain or insulating-member 22, is located within the upper end of said thimble 18, and secured in place by crimping the metal of said thimble around said insulating-member, to make 50 a tight joint between the two parts, and at the same time, take care of the expansion and contraction thereof, without cracking or breaking said porcelain or insulating member.

55 In the present illustration of this part of my invention, I have provided an annular recess or groove 23 upon the exterior of said insulating-member 22, in which is located a 60 gasket 24, against which an internal annular shoulder 25 on said thimble 18 is forced, by crimping said thimble, as previously described. See Fig. 4.

I have found, by long use and experimentation, that such crimping process is 65 entirely satisfactory, efficient, and permanent.

In the lower or inner end of the said binding-post insulating-member 22, is formed an outwardly-flaring recess 26, the upper end of which is in communication with the central bore 27 of said member. 70

Located in said central bore 27 of said insulating-member 22 is a long hollow cylindrical metallic base of the threaded binding-post 28; and this base also forms an elongated annular-member 29 of the amperage-booster, which will now be described in detail. 75

In the lower end of said base of said binding-post is formed a long vertical recess 30, the walls of which form said annular-member 80 29 of the amperage-booster.

Said annular-member 29 has an annular flange 31 at its lower end, which flange bears against the adjacent inner end of said flaring recess 26 of said insulating-member 22, and prevents upward or outward movement of said annular-member when the lock-nut 32 of said binding-post 28 is tightened up, in securing said parts in position upon said insulating-member. 85

Said lock-nut 32 may be provided with a recess 33 upon its under side, and a suitable washer 34 may be located in said recess, for an obvious purpose. Fig. 2. 90

The usual binding-post nut 35 is threaded upon the outer end of said binding-post 28. 95

The upper end of said central electrode 5 (which is carried by said main porcelain or insulating-member 6), is quite long, and it 100 extends upwardly a considerable distance within said vertical recess 30 of the said metallic base of said binding-post, centrally of the annular member 29 of the amperage-booster, and forms the other member of 105 said booster, as by such construction, there is an elongated annular space which extends a considerable distance parallel with and surrounding said centrally-located upper portion of the said central electrode 5, through 110 which the sparks jump consecutively at various coolest points, after the amperage has been sufficiently increased to cause them to jump thereat, and thence across the space separating the lower end of said central 115 electrode from said fixed electrode 4, with greatly increased strength, because of said built-up amperage. Fig. 3.

Thus I have provided an annular, or ring-like, spark-gap or intensifier, through 120 which the current may pass, either in a straight line from any part of the circumference of said annular member 29 to said central electrode 5, or in a circular or whirling path, within said annular member. 125

Said elongated amperage-booster, on account of its walls being parallel with the long upper portion of said electrode 5, enables the spark to jump always from the coolest part of said parallel walls to the 130

coolest part of the said electrode, no matter
said coolest parts be located at the upper
ends of said parts, or at the lower ends
thereof, or at any intermediate coolest point.
5 Said spark-producing parts will always
get quite hot at certain points, after sparks
have jumped between them for a consider-
able time; and this is true of all other spark-
plugs known to me; but by the use of my
10 improved construction, as above described,
the sparks are not confined to said hot
points, and jump always between the cooler
points, as the latter offer much less resist-
ance; thereby preventing missing, and keep-
15 ing the motor continually at its highest effi-
ciency.

The operation.

The operation and further advantages of
20 my invention will be readily apparent from
the above description.

I claim:—

In a spark-plug, a casing, a main insu-
lator seated in said casing, a binding-post
insulating-member having an annular-
groove in its outer surface; a gasket in said
annular-groove; a metallic-thimble holding
said main insulator in position and secured
upon said binding-post insulating-member
exterior of said gasket, around said annular-
groove, and a crimped annular-shoulder, on
said thimble to compress the gasket in said
groove, make a tight yielding joint between
said members, and at the same time securely
bind said metallic-thimble in place. 35

In testimony whereof, I have signed my
name to this specification in presence of two
subscribing witnesses.

LOUIS WOLLBRINCK.

Witnesses:

JOHN C. HIGDON,
HENRY L. HIGDON.
